[57]

CLAIM

The ornamental design for a softgel capsule, as shown and described.

DESCRIPTION

FIG. 1 is a perspective view showing my new design;
FIG. 2 is a top plan view thereof, the bottom plan view
being identical;
FIG. 3 is an end elevational view of the bulbous end;
FIG. 4 is a side elevational view, the opposite side being
identical; and,
FIG. 5 is an end elevational view of the smaller end.
